UNITED STATES PATENT OFFICE.

THOMAS E. SCULLY, OF LOS ANGELES, CALIFORNIA.

GARMENT TURNER.

Application filed September 18, 1920. Serial No. 411,133.

To all whom it may concern:

Be it known that I, THOMAS E. SCULLY, a citizen of the United States, residing at Los Angeles, in the county of Los Angeles and 5 State of California, have invented certain new and useful Improvements in Garment Turners, of which the following is a specification.

The present invention has reference to 10 means employed for turning gloves and other apparel right side out, after the sewing and finishing up of all the parts has been completed and is designed as an improvement over the device forming the subject 15 matter of U. S. P. N. 1,208,388 granted under date of Dec. 12, 1916.

The principal object of the present invention is to provide a device of the character specified wherein one of the apparel or 20 glove supporting rods is made sectional in character and adjustable to greater or shorter lengths at the will of the operator.

An additional object is to provide an improved type of glove holder in which the 25 movable rod of the apparatus is adjustably mounted through a support and spring-cushioned to yield easily under pressure as the operator forces the rods together for reversing the gloves.

30 With the above and other objects in view the invention may be said to reside generally in the details of construction, combination and arrangement of parts as will be herein-after more fully pointed out and described, 35 reference being had to the accompanying drawings wherein;

Figure 1 is a side elevation of a device constructed in accordance with the invention, and

40 Figure 2 is a sectional view taken longitudinally of the movable rod of the apparatus.

Referring now to the drawing the numeral 1 indicates the supporting frame or bracket, 45 preferably a metallic structure and consisting of an elongated flat bar, having unequal end portions 2 and 3 bent upwardly from the base as illustrated. The end 3 projects upwardly at about right angles and 50 is provided with terminal portions 4 inclined to the vertical and extending in parallelism with end 2 which is likewise inclined. The bracket is adapted to be suitably fastened to a support and carry the glove holding members 5 and 6 both of which are arranged in 55 axial alignment with each other as shown.

Member 5 consists of a tapered stock having a threaded stud 5' inserted through end 2 and fastened securely thereto by a nut 7. At the innermost end of the stock a cylindrical rod of slender proportion is formed, being connected to stock 5 by a beveled portion 8. The rod or stick 9 is of even diameter and provides a support upon which the thumb and fingers of a glove are successively placed, with the stitched or sewed side outermost.

The tapering body or stock 6 of the other member is rigidly fastened to the end 4 by means of a nut 10 which threads about the 70 threaded shank 11, projecting through the bracket end. This stock is also provided with a smooth faced bore 12 through which slides a stick or rod 13, the latter being provided with a beveled collar 14 for abutment 75 with the end of the stock to limit upward movement of the rod. The bore is enlarged adjacent the upper end of the stop to provide a cushioning chamber 15 within which is mounted a coiled spring 16 encircling the 80 threaded end 17 of the slidable rod. Inserted partially into the chamber is a sleeve 18 having an enlarged, shoulder forming an annular head arranged for abutment with the end of stop projection 11. This sleeve is 85 provided with a threaded bore so that it may be screwed upon the end of the slidable rod with its innermost end pressing against and compressing spring 16, as the rod slides downwardly through the tapering stock or 90 guide. The parts are held in position by means of a handle knob 19 screwed upon the threaded end of the slidable rod and abutting with the enlarged head of sleeve 18. The knob provides convenient grip means 95

for permitting the rod 13 to be manually shifted up and down through the guide stock 6. The parts may be adequately lubricated through oil holes 20 formed in the stock and lock nut 10.

In the operation of the device, after the stitched glove has been arranged upon the holder 5 in a manner previously described, that is with a thumb or finger over the projecting portion 9 thereof, the operator, by applying pressure to knob 19, forces the rod 13 downwardly through stock 6, until the head 18 abuts with the extension 11. The sleeve being screw threaded upon the rod and adjustable it is obvious that the point of abutment may be varied so that the sliding rod may be brought to a stop with its tapering

end 21 in spaced relation to the end of stick 9 or the ends may be permitted to contact. Usually the rod is slid forward until it contacts with the opposite rod, the end of the thumb or finger portion of the glove being thus securely held between the two rods. Upon drawing the glove forward and over upon rod 13, the stitched portion of the finger supported upon the rod will be turned 10 inwardly and the finished end outwardly. Upon releasing pressure on knob 19, spring 15 automatically shifts sleeve 18 outwardly, thus returning the rod 13 to starting position, as illustrated in Figure 1 of the drawings. In this way, each finger and thumb 15 of a glove is successively reversed, the enlarged body portions or stocks 5 and 6, in each case providing a convenient rest for the palm and wrist portion of the glove during 20 the operation.

It is to be noted that the movable holder of the device is comprised of parts easily separated and capable of being taken apart or put together whenever required. The spring 25 tends to return the rod to its original position and the sleeve enables the operator to control the movement of the rod so that the stroke can be either lengthened or shortened.

It is believed that the advantages of the 30 adjustable rod structure tend to provide a more compact and simple structure capable of fast work and easy to operate.

Having thus described my invention what I claim as new and desire to secure by Letters Patent is:—

1. A glove turning device comprising a support, an article receiving member fixed at one end of the support, a second article re-

ceiving member detachably secured at the other end of said support, a rod slidably 40 mounted in the second mentioned article receiving member, said second mentioned article receiving member consisting of a hollow tapering body provided with an enlarged chamber, a sleeve adapted to fit into the enlarged chamber, said sleeve threaded on the said slideable rod and having an enlarged head provided at its outer end, a coil spring arranged in the enlarged chamber and encircling the sliding rod and having one end 50 resting against the inner end of the threaded sleeve, and means arranged on the end of said sliding rod to actuate the same, and means carried by said rod to limit the return of said rod.

2. A glove turning device comprising a support, an article receiving member fixed at one end of the support, a second article receiving member detachably secured at the other end of said support, said second mentioned article receiving member consisting of a tubular stationary member, a rod slidably mounted therein and having its ends extending beyond the ends of the said stationary tubular member, a spring associated with 60 the rod for normally retaining the forward end of the rod spaced from the stationary member, and means for limiting the sliding movement of the rod in the tubular body.

In testimony whereof, I affix my signature 70 in presence of two witnesses,

THOMAS E. SCULLY.

Witnesses:
